FLORAL BASKET OR SIMILAR ARTICLE

Robert E. Wilson, Pittsburgh, Pa., assignor to Stylette Plastics, Inc., Oakdale, Pa., a corporation of Pennsylvania

Filed Jan. 23, 1969, Ser. No. 15,459

Term of patent 14 years

Int. Cl. D9—05

U.S. Cl. D9—246

Fig. 1

Fig. 2

Fig. 3

FIG. 1 is a side elevational view of a floral basket showing my new design;

FIG. 2 is a plan view of the floral basket of FIG. 1; and

FIG. 3 is an end elevational view of the floral basket, taken at 90° from the view of FIG. 1.

The other side and end are substantially like the respective side and end shown. The bottom of the basket is plain.

I claim:

The ornamental design for a floral basket or similar article, substantially as shown and described.
